UNITED STATES PATENT OFFICE.

CHARLES N. MARTIN, OF WILLIMANTIC, CONNECTICUT, ASSIGNOR OF ONE HALF TO ARTHUR P. BENNER, OF SAME PLACE.

LET-OFF FOR LOOMS.

SPECIFICATION forming part of Letters Patent No. 530,647, dated December 11, 1894.

Application filed February 9, 1893. Serial No. 461,629. (No model.)

To all whom it may concern:

Be it known that I, CHARLES N. MARTIN, of Willimantic, in the county of Windham and State of Connecticut, have invented certain new and useful Improvements in Let-Offs for Looms, of which the following is a full, clear, and exact description whereby any one skilled in the art can make and use the same.

10 The object of my invention is to provide an attachment for a cloth weaving loom that can be used in connection with the warp beam in such manner as to insure an even tension of the warp threads and a consequent even appearance of the woven cloth.

To this end my invention consists in the details of the several parts with each other and the mechanism of the loom as more particularly hereinafter described, and pointed out in the claims.

Referring to the drawings: Figure 1 is a detail view in elevation of a loom showing the manner of applying the attachment. Fig. 2 is a detail view in central section through the let-off. Fig. 3 is a detail view of the attachment looking from the frame with parts broken away to show construction. Fig. 4 is a detail view in central section of the brake. Fig. 5 is a detail plan view of the friction plate. Fig. 6 is a detail edge view of the same showing the spring on the pins. Fig. 7 is a detail plan view of the back of the gear wheel forming part of the brake section. Fig. 8 is a detail view in crosswise central section through the brake section. Fig. 9 is a detail view showing the connection between the whip roll and the shipping rod and the forked end of the latter. Fig. 10 is a detail face view of the collar showing the beveled surface.

In the accompanying drawings the letter *a* denotes the end part of the frame of a loom adapted for weaving cloth; *b*, the warp beam pivotally supported on the frame; *c*, the warp threads, and *d* the whip roll over which the warp threads pass from the beam toward the front of the loom.

The warp thread is unwound by a rotary movement of the warp beam imparted to it by means of a train of gear wheels that are connected with a gear wheel *e* secured to

the main shaft *e* of the loom. A short shaft *f* is mounted in bearings in the frame and has on its outer end a gear wheel *f'* and on its inner end a gear wheel *f''*, the latter being in mesh with a gear wheel *b'* fast to the shaft of the warp beam. It is only at certain times during the weaving that the warp threads are allowed to be fed forward by the rotary movement of the warp beam and the latter is released and driven by the let-off device that is automatically operated by the movement of the whip roll *d*. An arm *d'* fast to this whip roll supports a shipping rod *g*, the lower end of which is provided with a wedge *g'* that is forked and is adapted to operate a sliding collar *h* that forms part of a friction clutch *i*. This collar *h* is beveled on its upper surface on the side toward and in opposition to the shipping rod *g* as shown in Figs. 1 and 10 of the drawings, the collar having a free sliding movement on the stud *k*. The square end of this collar pressing against the gear *n²* in contact with the clutch section *n* forces the flange of the latter into contact with the gear *l*, this operation of the parts being caused by the downward movement of the shipping rod *g*.

A stud *k* is secured to the end *a* of the frame as by means of a shoulder *k'* on the stud and clamping the frame between this shoulder and a nut *k''* secured upon the end of the stud that projects through an opening in the frame. On this stud is supported a gear wheel *l* in mesh with the gear wheel *e'*, the gear *l* being normally free to rotate on the stud and having a constant motion communicated from the gear wheel *e'* when the loom is in operation. There is a socket *l'* formed on the inner side of this gear wheel and in the socket is located a friction disk *m* of soft material, as leather, between the bottom of the socket and the face of a flange *n'* formed on the clutch section *n*, the hub of this latter part having a gear wheel *n²* the side of which is in contact with the collar *h*. Within this body part of the clutch section *n* is a socket *n³* in which is located a spring plate *n⁴* seated on a disk *n⁵* of soft material as leather, the springs *n⁶* seated on the spring plate *n⁴* thrusting outward against a face plate *n⁷*, the outer face of which is in contact with the

friction disk *m*. By means of these springs the larger part of the surface of the flange *n*' is held normally out of contact with the friction plate but by a downward movement of 5 the arm *d*' the wedge *g*' through the intermediate shipping rod *g* thrusts the collar outward and forces the flange of the clutch section into contact with the friction plate holding against this surface with sufficient tenacity to rotate the warp beam through the medium of an intermediate gear *o*. The latter is mounted on a pin secured to the lever arm *p* that is pivotally mounted on the stud *k*. As soon as the whip roll rocks back the wedge 15 is lifted and the springs within the clutch body operate to thrust the sections apart so that the gear wheel *l* will continue to revolve without carrying with it the train of gears that drive the warp beam.

20 In order to prevent any return motion or back lash of the warp beam a friction break *q* is connected to the intermediate gear *o*. This comprises a socket piece *r* secured to the lever arm *p*, a disk *r*' of soft material, 25 preferably of leather, and a spring plate *s* having the pins *s*' that project into sockets *o*' in the side of the gear *o*. On these pins are arranged springs *o*'' that are seated against the spring plate and in the sockets in the 30 side of the gear wheel in such manner as to thrust the latter outward with a yielding pressure. On the outer side of the gear wheel a socket is formed and in it is arranged a friction plate *t* of leather, a cap *t*' covering 35 the plate and having a square opening fitted upon a squared portion of the pin so as to hold the cap against rotation. By this device the gear wheel is held on the pivot or pin by the frictional grasp of the plate *t* against the 40 bottom of the socket in the gear and the disk *r*' against the bottom of the socket piece *r*. The parts are held together by means of nuts *t*'' that fit upon the threaded end of the pin.

The function of the brake is to control the 45 rotary movement of the intermediate gear *o* so that as soon as the driving power communicated to it by the rotary movement of the gear on the clutch body part is removed the intermediate gear *o* will immediately stop in its 50 rotary movement, the brake holding it with sufficient power to prevent any continued revolution of the warp beam from any recoil of the beam. By means of this let-off device the warp threads are delivered from the beam 55 under an even tension and the beam will run at a uniform speed from a full beam until it is emptied or all the warp thread has become unwound and it will do this without change of tension. By means of this improved construction of the let-off it has been shown by 60 test in the running of looms for weaving cloth that an increase in the percentage of cloth woven in a given time is obtained owing to the great uniformity of the tension and delivery of the warp thread from the beam.

65 A further object of my improved let-off device is that it is so arranged that an opera-

tive cannot tamper with it to change the tension of the thread to allow a freer delivery as is the case with many of the old forms of 70 let-offs.

The brake device is so inclosed that it is not liable to become injured or made inoperative by accidental introduction of any foreign matter between the operative parts. 75

I claim as my invention—

1. In a let off mechanism for looms, in combination with the frame, a stud secured thereto, a gear wheel mounted to rotate loosely on said stud and in mesh with the main driving 80 gear of the loom, a clutch section located in the loosely mounted gear wheel and adapted to frictionally engage the same, a pinion secured to the clutch section and adapted to rotate the warp beam, the warp beam, a sliding collar mounted on the stud with one side engaging with the gear secured to the clutch section and its opposite side bearing a cam face, a wedge having one end adapted to engage the cam face of the collar and its opposite end connected with the whip roll, and the whip roll, all substantially as described. 85

2. In a let off mechanism for looms, in combination with the frame, a stud secured to the frame, a gear wheel mounted to rotate on the 95 stud, a spring actuated clutch section loosely mounted on the stud and within said gear wheel and adapted to frictionally engage the same, a gear secured to the clutch section and adapted to rotate the warp beam, the 100 warp beam, a collar loosely mounted on the stud with one side engaging the gear on the clutch section and the other side having a cam face, a wedge with one end resting against the cam face of the collar and the other end 105 operatively connected with the whip roll, and the whip roll, all substantially as described.

3. In a loom, in combination with the warp beam, a flanged clutch section having secured thereto a gear adapted to rotate the 110 warp beam, a stud on which the clutch section is loosely mounted, a sliding collar mounted on the stud with one end engaging the gear secured to the clutch section and the other end bearing a cam face, a wedge having one end resting against the cam face of the collar and the other end 115 operatively connected with the whip roll, the whip roll, a gear wheel mounted to rotate on the stud, a socket on the inner side of said gear wheel 120 containing an elastic disk, the elastic disk, a socket located in the clutch section, an elastic disk secured therein, a spring plate bearing against the elastic disk, springs seated upon the spring plate and normally pressing 125 against a face plate, and the face plate adapted to engage the elastic disk on the gear mounted on the stud whereby the clutch sections are thrown into engagement by the downward movement of the wedge, all substantially as described. 130

4. In a let off mechanism for looms in combination with the frame, a gear wheel loosely mounted thereon and having a socket, an elas-

tic disk located in the socket, a clutch section having an annular flange located in the socket in said gear, a socket located in the clutch section, an elastic disk located in the 5 socket in the clutch section, a spring plate, and a face plate with springs interposed therebetween located in the socket in the clutch section whereby a yielding contact between the face plate and the elastic disk in the gear 10 wheel is obtained, a shifting lever connected with and operated by the whip roll of the loom to throw the clutch sections into and out of operative engagement, and the whip roll, all substantially as described.

15 5. In a let off mechanism for looms, in combination with the clutch mechanism controlling the movement of the warp beam, the warp beam, an automatic friction brake comprising a gear wheel interposed between the 20 clutch mechanism and the warp beam of the

loom and operatively connected therewith, a cap located in said gear wheel and fixed to the stud upon which said wheel rotates, the stud, a friction plate interposed between the cap and bottom of the socket in the wheel, a 25 socket piece secured to an arm supporting the said stud, the arm, a friction disk located in the socket piece, a spring plate resting against the friction disk, pins secured to said plate and projecting into sockets in the gear wheel, 30 and springs located on said pins and thrusting against the spring plate and gear to force the latter outward and impinge the friction disks with a yielding pressure, all substantially as described.
